UNITED STATES PATENT OFFICE.

EDGAR B. SYMONS, OF MILWAUKEE, WISCONSIN.

STONE CRUSHER AND PULVERIZER.

1,145,629.

Specification of Letters Patent.

Patented July 6, 1915.

Application filed April 17, 1911. Serial No. 621,482.

To all whom it may concern:

Be it known that I, EDGAR B. SYMONS, citizen of the United States, residing at Milwaukee, in the county of Milwaukee and

5 State of Wisconsin, have invented a certain new and useful Improvement in Stone Crushers and Pulverizers, of which the following is a specification.

10 My invention relates to improvements in crushing machines as illustrated diagrammatically in one form in the accompanying drawing wherein—

15 Figure 1 is a vertical section through the machine; Fig. 2 a section along the line 2—2 of Fig. 1, with parts removed; Fig. 3 a section along the line 3—3 of Fig. 1, with parts removed; Fig. 4 is an axial section of one of the crushing rolls; Fig. 5 a detail top plan view of one of the crushing rolls; Fig. 20 6 a detail section along line 6—6 of Fig. 5; Fig. 7 a detail section along the line 7—7 of Fig. 2.

Like parts are indicated by like letters in all the figures.

25 The cylindrical base A is provided at its bottom with the inwardly extending radially disposed hollow housing A¹ forming with the two radial arms A² a spider arm the bottom of which supports the upwardly projecting sleeve A³ and the cylindrical closed bottom casing A⁴ which terminates at one side in a downwardly extending pocket A⁵ in one wall of which is located a screw threaded removable plug A⁶. The holding

30 ring A⁷ which is slidably mounted upon the top of the base A is adjustable thereon by means of the three set screws A⁸ screw threaded in the lugs A⁹ and in opposition to the top of the base A and may be held

35 40 in position upon the base by the holding bolts A¹⁰ engaging the slots A¹¹. The inner surface of the ring A⁷ is upwardly and outwardly flaring and is bounded at the bottom by the inwardly extending flange A¹² which

45 supports the removable crushing ring A¹³ held in position against the backing A¹⁴ by the annular ring A¹⁵ bolted to the flange A¹⁶ about the top of the holding ring A⁷.

The rigid shaft B projects upwardly from the sleeve A³, is held in position therein by the collar B¹ engaging the top thereof and carries pinned to its upper end the bearing cap B² in opposition to a bearing disk B³ pinned to the head B⁴ which in turn is bolted to the top of the sleeve B⁵. The sleeve B⁵ contains the anti-friction bearing B⁶ in

opposition to the upper end of the shaft B and the anti-friction bearing B⁷ in opposition to the sleeve A³. The flange B⁸ projects outwardly from the base of the sleeve B⁵ and overhangs the cylindrical casing A⁴ and is provided with the downwardly depending cylindrical wall B⁹ within said casing and the downwardly depending cylindrical wall B¹⁰ outside of said casing. 60 The miter gear B¹¹ is keyed to the sleeve B⁵ and is in engagement with the miter pinion B¹² keyed to the driving shaft B¹³ which is rotatably mounted in the anti-friction bearings B¹⁴ B¹⁵ in the hollow housing A¹, the bearing B¹⁵ being partially contained in the housing B¹⁶ outwardly projecting from the base A. The driving pulley B¹⁷ is keyed to the driving shaft B¹³ at its outer end. 65

70 The cradles C which are held slidably upon the flange B⁸ by the overhanging guides C¹ are drawn up against the spacing shims C² by the nuts C³ which engage the lugs C⁴ and are mounted upon the bolts C⁵ which project from the flat sides of the triangular member C⁶ on the sleeve B⁵. The parallel lugs C⁷ project upwardly from the cradle C and carry the shafts C⁸ upon which are rotatably mounted the knuckles C⁹ from which project upwardly the shafts C¹⁰. The 75 flange C¹¹ is mounted upon the shoulder C¹² on the knuckles C⁹, supports the annular bearing ring C¹³ about the shaft C¹⁰ and is provided with the upwardly and inwardly extending wall C¹⁴ forming an oil ring C¹⁵ 80 90 which terminates at its outer side in the oil chamber C¹⁶.

95 The crushing roll D which is rotatably mounted upon the shaft C¹⁰ and is provided with the truncated conical crushing portion D¹ in opposition to the crushing ring A¹⁸, is supported at its base upon the bearing ring C¹³ and is provided with the outwardly projecting shoulder D² in opposition to the upper edge of the wall C¹⁴. The guiding 100 block D³ which is slidably mounted upon the upper end of the shaft C¹⁰ is provided with the downwardly projecting cylindrical member D⁴ in opposition to the top of the roll D and inclosing the collar D⁵ and packing washer D⁶. The nut D⁷ screw-threaded upon the shaft C¹⁰ engages the upper surface of the block D³ to hold it against the roll. The set-screw D⁸ is screw-threaded in the shaft C¹⁰ and engages the cross bar D⁹ 105 110 which is slidably mounted in the transverse slot D¹⁰ and engages at either end the keys

- D¹¹ which bear upon the collar D⁵ to compress the washer D⁶ to prevent the escape of oil from the bearing. The nut D⁷ is provided with a plurality of key ways D¹² in opposition to a single key way D¹³ in the shaft C¹⁰ and may be held against rotation about said shaft by the key D¹⁴ held in position by the cotter pin D¹⁵ in the lugs D¹⁶.
- The block D³ which is in slidable engagement with the guiding arms E in the ring E¹ rigidly attached to the lugs E² on the sleeves B⁵, is in engagement on its upper side with the T-shaped spacing shims E³ held in position on the benches E⁴ by the fixed plates E⁵. The cap B⁴ is provided with the upwardly extending hollow shaft E⁶ which carries the circular disk E⁸, and is provided with the lug E⁹ engaging the lug E⁷ projecting from the disk E⁸.
- The disk E⁸ overhangs the inner edge of a truncated conical guide or chute E¹¹ which overhangs at its outer edge the annular ring A¹⁵ at the top of the crushing ring and is suspended from the housing E¹² which is supported on the cylindrical ring E¹³ and is provided with the centrally disposed chute E¹⁴.

The oil pipe F leads from any suitable oil tank not shown to the chamber F¹ in the base of the sleeve A³ from which leads the oil passage F² through the shaft B to the bearing surface between the cap B² and the disk B⁸ which bearing surfaces are surrounded by the oil chamber F³. The oil pipe F⁴ leads from the chamber F³ to the top of the shaft C¹⁰ and communicates with the oil passage F⁵ which communicates with the spiral oil groove F⁶ in the outside of the shaft. The groove F⁶ leads spirally around the shaft to the oil chamber C¹⁶ from which leads the oil pipe F⁷ to the pipe F⁸ which discharges into the interior of the cylindrical casing A⁴. The passages F⁹ leads from the cylindrical casing A⁴ to the interior of the housing A¹ to oil the bearings B¹⁴, B¹⁵. The oil pipe F¹⁰ leads from the pocket A⁶ back to the tank not shown. The outer end of the bearing B¹⁶ is in opposition to the cup-shaped flange F¹¹ on the shaft B¹³ and is surrounded by the oil-containing pocket F¹² from which leads the pipe F¹³ communicating with the pipe F¹⁰. The annular ring G is supported on the foundation beams G¹ below the spider-arm bottom and carries the rotatable chute G².

It will be evident that while I have shown in my drawings, an operative device still many changes might be made in the size, shape and arrangement of the parts without departing materially from the spirit of my invention.

The use and operation of my invention are as follows: My ring roll crusher is capable of taking in material the particles of which differ in size through a wide range.

The smaller particles will begin to slide down along the crushing surface of the ring not being attacked until they reach the lower part but while they are so moving the larger particles are being crushed between the upper diverging crushing surfaces and thus there is a simultaneous crushing action on particles of greatly varying sizes, the larger particles being crushed at the top and the finer ones at the bottom of the ring. The ring and roll may of course be set or inclined in various ways or their surfaces shaped in various ways so as to get these results. The essential point with regard to the matter at this moment under consideration is the feeding of the material in the direction of the length of the roll while subjecting particles of varying sizes simultaneously to the crushing action. For convenience the surfaces are so arranged that they present in effect two or more crushing zones in the lower of which the crushing surfaces are practically parallel or nearly so, while in the upper zones they rapidly and widely diverge. The zones of divergence should be much wider than the zones of parallelism because there will be much less work done per unit of area in the upper than in the lower zones. The preferred form is that in which the ring is curved and outwardly and upwardly flaring as shown.

The ring is made preferably of manganese steel, which, of course, it is practically impossible to work, and it should be shaped properly in the beginning. The roll preferably thickens downwardly because the particles being smaller there is more work to be done at the lower part of the roll than at the upper part.

In the case of centrifugally actuated outwardly swinging crushing rolls in ring roll machines the roll if it contacts or is free to contact the surface of the ring tends to destroy or pit it. If an unusually difficult or hard particle is encountered the tendency will be to dent or recess the surface of the ring especially if a defective spot therein be found. The tendency of the roll, of course, having found or made a weak spot in the ring, is to follow it up and continue to batter it in, the bottom of the hole being farther from the center of rotation than any other part of the surface of the ring. This is effectually prevented by arranging the roll so that it has a stop which prevents its actually contacting the surface in front of it. By making the stop adjustable it becomes in effect an adjustable bearing and the gap therefor at the time of crushing, between ring and roll, may be varied. The roll is pivoted below so that any such adjustment tends to widen the gap above more than it does below but in order to give the widest possible range of ad-

justment the bearings for both ends of the roll are adjustable so that the roll may be moved bodily without varying the angle of divergence and may take therefor the 5 raw material at any desired maximum cross section and deliver it at any desired maximum cross section. Such a machine made at any size to suit and may perform the function of a gyratory crusher at the top 10 of the ring while it performs the function of a pulverizing or powdering machine at the bottom of the roll on the same material. By having the supports of the ends of the rolls made so that either may be adjusted 15 in either direction any desired arrangement can be obtained. The roll is preferably inclined outwardly at the time when it crushes. The resultant of the forces then at work is such as to counteract the gravity of the roll itself and take 20 the burden off of the lower portion of the roll.

In my description of claims I speak generally of a roll but it is of course understood 25 that there will be any desired number of rolls each mounted and operating preferably in the same manner as all the others. The machine may be shaped so as to take in the material in a very coarse condition and 30 deliver it in a very fine condition or it may take in the material in a very coarse condition and leave it in a relatively coarse though much finer condition and it may also pass the material through without very greatly 35 reducing the diameters of its particles.

By having a free and unobstructed discharge chamber below the ring the material passes with a free fall by the action of gravity down over or along the surface of 40 the crushing roll and into the discharge chamber and is never piled up in around the rolls or banked against the crushing ring. This feed is conveniently effected by the rotating distributing disk which prefer- 45 ably piles up the material on a ledge above the ring when it swings gently down over the ring. The rate of rotation of the rolls may be varied but it should be such that any given particle will pass a roll a number of 50 times in the course of its descent from the top of the ring to the bottom of the ring so that it will have many opportunities to pass under and be attacked by one of the rolls. The proportions of the parts can, of course, 55 be varied to suit. The feed is in effect a free, cylindrical film of material not packed or banked but thinly distributed on a surface over which the roll travels and such mate- 60 rial has a free gravity discharge below the ring and performs a complete excursion from the top of the ring down along its surface and out of the machine.

The length of the rolls and the width of the ring are such that each particle falling 65 by gravity along the inner surface of the

ring will continue its excursion so long that a series of blows may be given it by the passing rollers and the feed should be so distributed that in effect a reduction blow is given to each separated particle. Experience 70 demonstrates that in crushing by means of a ring and roll it is best to reduce to a limited degree, that is, for example, to so operate as that any given blow will reduce those particles of the maximum size 75 fed to the machine to say one-third or one-quarter of their respective diameters. To effect any greater reduction, therefore, the rolls and rings must be shaped and related so that there will be a series of such reduc- 80 tion blows, each reducing its maximum particles to one-quarter size. This I accomplish in my invention by varying the distance between the crushing roll and the ring at different points along the line of travel 85 of the material fed. Thus, for example, a particle near the top of the roll if two inches in diameter might be broken to a series of particles one-half inch in diameter, and these farther down the roll would be again struck 90 and reduced from one-half to particles of a size not exceeding one-eighth inch in diameter. If as above suggested each particle is to be received and be reduced in a separated condition by a blow then the feed must be 95 such that these particles as they are successively crushed or broken will each find itself in effect segregated so as to have about it an area into which it can be expanded or flattened or the particles into which it has been 100 crushed be distributed. By so feeding and so arranging the rolls the particles can be reduced from a relatively large to a relatively small size. For such an action to have its full opportunity to work the de- 105 sired results the particles must have a free gravity fall or its substantial equivalent through the crushing members as distinguished, for example, from a gyratory where all the particles are held in the top of the 110 machine, and from that form of roll ring machine in which the rolls travel in a mass of material or where the loose material is packed or rolled out into a cushion as it were between the roll and ring.

115 I claim:

1. In a ring roll crushing machine the combination of a crushing ring having an open bottom with an upright roll revolving therein and traveling therealong said roll 120 upwardly and outwardly inclined to the vertical during the crushing operation.

2. In a ring roll crushing machine the combination of a crushing ring with an upright roll revolving therein and therealong 125 the roll mounted in bearings at top and bottom said bearings adjustable to move the lower end of the roll bodily to and from the ring and to limit the upper end of the roll toward the ring.

3. In a ring roll crushing machine the combination of a crushing ring with an upright roll revolving therein and therealong the roll mounted in bearings at top and bottom one of said bearings adjustable so as to give variable inclinations to the roll at various crushing operations.
4. In a ring roll crushing machine the combination of a crushing ring with an upright roll revolving therein and therealong the roll mounted in bearings at top and bottom both of said bearings adjustable so that either roll end may be varied in either radial direction.
5. In a ring roll crushing machine the combination of a crushing ring with an upright roll revolving therein and therealong their opposed crushing surfaces upwardly diverging and means for moving the roll bodily to and from the ring to vary the width of the gap between them.
6. In a ring roll crushing machine the combination of a crushing ring with an upright roll revolving therein and therealong, said machine being provided with a free, unobstructed discharge passage below the ring and means for feeding a film of material to be crushed continuously past the ring surface.
7. In a ring roll crushing machine the combination of a crushing ring with an upright roll revolving therein and traveling therealong, the crushing surface of the ring provided with zones at an inclination to each other.
8. In a ring roll crushing machine the combination of a crushing ring with an upright roll revolving therein and traveling therealong, their opposed simultaneously acting crushing surfaces at varying distances from each other.
9. In a ring roll crushing machine the combination of a crushing ring with an upright roll revolving therein and traveling therealong, their opposed simultaneously acting crushing surfaces at varying distances from each other, such distances diminishing in the direction of forward feed.
10. In a ring roll crushing machine the combination of a crushing ring with an upright roll revolving therein and therealong, their opposed crushing surfaces upwardly diverging and means for feeding a cylindrical film of material along the crushing surface of the ring.
11. In a ring roll crushing machine the combination of a crushing ring with an upright roll revolving therein and therealong, a material ledge around the upper edge of the ring, means for supplying material to said ledge and an unobstructed discharge opening at the bottom of the ring so that a film of material is fed continuously over the crushing of the ring.
12. In a ring roll crushing machine the combination of a crushing ring with an upright roll revolving therein and therealong, their opposed crushing surfaces upwardly diverging and nowhere parallel to the horizontal and supports for the roll whereby when revolved it moves under centrifugal force toward the ring.
13. In a ring roll crushing machine the combination of a crushing ring with an upright roll revolving therein and therealong, said roll pivotally secured at its lower end and free to swing radially at its upper end, and an adjustable stop to limit such radial movement in the direction of the ring.
14. In a ring roll crushing machine the combination of a crushing ring with an upright roll revolving therein and therealong, said roll pivotally secured at its lower end and free to swing radially at its upper end and means for adjusting the position of the pivotal bearing toward or from the ring.
15. In a ring roll crushing machine the combination of a crushing ring with an upright roll revolving therein and therealong, said roll pivotally secured at its lower end and free to swing radially at its upper end and means for adjusting the position of the pivotal bearing toward or from the ring and a variable stop to limit the radial motion of the roller.
16. In a ring roll crushing machine the combination of a crushing ring with an upright roll revolving therein and therealong, means for holding the roll during the crushing operation at a distance from the crushing surface of the ring and means for continuously feeding an unobstructed film of material between the crushing surfaces.
17. In a ring roll crushing machine the combination of a crushing ring with an upright roll revolving therein and therealong, their opposed crushing surfaces upwardly diverging and means for separating them bodily without disturbing such divergence.
18. In a ring roll crushing machine the combination of a crushing ring with an upright roll revolving therein and therealong, their opposed crushing surfaces upwardly diverging and means for separating them bodily to widen the gap between them.
19. In a ring roll crushing machine the combination of a crushing ring with an upright roll, means for revolving the same in and along the crushing ring so that the roll is moved toward the ring by centrifugal force and means for arresting the outward movement of the roll at a predetermined distance from the ring and means for continuously feeding an unobstructed film of material between the crushing surfaces.
20. In a ring roll crushing machine the combination of a crushing ring with an upright roll revolving therein and traveling

therealong, their opposed crushing surfaces upwardly diverging and increasing in cross section downwardly.

21. In a ring roll crushing machine the combination of a crushing ring with an upright roll revolving therein and therealong, said roll mounted so that it moves radially toward the ring under the influence of gravity and means for preventing its contact with the ring and means for continuously feeding an unobstructed film of material between the crushing surfaces.

22. In a ring roll crushing machine the combination of a crushing ring with an upright roll revolving therein and therealong and means for feeding a cylindrical continuous film of material along the crushing surface of the ring and for giving a free fall and gravity discharge for such material across and below the ring.

23. In a ring roll crushing machine the combination of a crushing ring with an upright roll revolving therein and therealong, their opposed crushing surfaces upwardly diverging and a rotating distributing disk to discharge the material by centrifugal force in a cylindrical film to the crushing surface of the ring.

24. In a ring roll crushing machine the combination of a crushing ring with a central shaft, a sleeve thereon, a crushing roll mounted on the sleeve and means for driving the sleeve so as to rotate the roll within and along the crushing surface of the ring, their opposed crushing surfaces upwardly diverging.

25. In a ring roll crushing machine the combination of a crushing ring with a central shaft, a sleeve thereon, a crushing roll mounted on the sleeve and means for driving the sleeve so as to rotate the roll within and along the crushing surface of the ring, the ends of the roll projecting beyond the top and bottom of the ring.

26. In a ring roll crushing machine the combination of a crushing ring with a fixed central shaft, a sleeve thereon, a crushing roll mounted on the sleeve and means for driving the sleeve so as to rotate the roll within and along the crushing surface of the ring, the upper end of the roll adapted to swing radially on the sleeve.

27. In a ring roll crushing machine the combination of a crushing ring with a fixed central shaft, a sleeve thereon, a crushing roll mounted on the sleeve and means for driving the sleeve so as to rotate the roll within and along the crushing surface of the ring, the lower end of the roll pivoted and the upper end adapted to swing radially on the sleeve.

28. In a ring roll crushing machine the combination of a crushing ring with a central shaft, a sleeve thereon, a crushing roll

mounted on the sleeve and means for driving the sleeve so as to rotate the roll within and along the crushing surface of the ring, the lower end of the roll pivoted and the upper end adapted to swing radially on the sleeve and a stop to limit the radial swing of said roll toward the ring.

29. In a ring roll crushing machine the combination of a crushing ring with a central fixed shaft, a sleeve thereon, means for rotating the sleeve and an upright roll mounted on the sleeve and secured thereto at both ends.

30. In a ring roll crushing machine the combination of a crushing ring with a central fixed shaft, a sleeve thereon, means for rotating the sleeve and an upright roll mounted on the sleeve and secured thereto at both ends, the lower end by a pivot.

31. In a ring roll crushing machine the combination of a crushing ring with a central fixed shaft, a sleeve thereon, means for rotating the sleeve and an upright roll mounted on the sleeve and secured thereto at both ends, the lower end by a pivot and the upper end so as to be free to swing radially.

32. In a ring roll crushing machine the combination of a crushing ring with a fixed shaft in the center thereof, a sleeve mounted on the shaft, means for rotating the sleeve mounted below the ring and a crushing roll mounted on the sleeve.

33. In a ring roll crushing machine the combination of a crushing ring with a fixed shaft in the center thereof a sleeve mounted on the shaft means for rotating the sleeve mounted below the ring and a crushing roll mounted on the sleeve and free to move radially out from it and a hood and frame to entirely inclose all the parts.

34. In a ring roll crushing machine the combination of a cylindrical frame a ring roll mounted in the upper part thereof, a shaft fixedly supported in the center of the ring and frame a sleeve mounted on the shaft, means for rotating the sleeve, a crushing roll mounted on the sleeve, said machine being provided with a free and unobstructed discharge opening through the cylindrical frame below the ring and a hood to cover the top of the ring and rolls.

35. In a ring roll crushing machine a combination of a crushing ring with a central shaft, a sleeve mounted thereon, two projecting parts at top and bottom of the sleeve, means for rotating the sleeve and a crushing roll mounted on the sleeve in such projecting parts.

36. In a ring roll crushing machine a frame, a crushing ring mounted therein, an upright crushing roll within the ring, means for revolving it and a disk like material distributor forming a cap or cover for the roll

and its supporting or driving mechanism and adapted to deliver a film of material to the surface of the ring.

37. In a ring roll crushing machine the combination of a frame with a crushing ring mounted thereon and connections between the two consisting of vertical and horizontal bolts and screws whereby the ring may be centered and secured on the frame from a central shaft, a sleeve thereon, means for rotating it and upright rolls mounted on the sleeve.

38. In a ring roll crushing machine the combination of a crushing ring with a central shaft fixedly mounted therein, a sleeve mounted on the shaft, an upright roll carried by the sleeve, means for rotating the sleeve and an inclosing box to contain the

driving gears and channels, and connections whereby the interior of the sleeve, the box ²⁰ and the interior of the crushing roll form a circular passage for oil.

39. In a ring roll crushing machine the combination of a crushing ring with an upright roll revolving therein and traveling ²⁵ therewith, their opposed crushing surfaces upwardly diverging, said machine being provided with a free unobstructed discharge passage between the crushing surfaces and out of the machine and means for supplying ³⁰ a film of material to be crushed between the crushing surfaces.

EDGAR B. SYMONS.
